SIGN FLASHING DEVICE

Thomas J. Mudon, Chicago, Ill., assignor, by direct and mesne assignments, to Cires Products Corporation, Chicago, Ill., a corporation of Illinois

Application February 8, 1934, Serial No. 710,244

1 Claim. (Cl. 200—27)

My invention relates to flashing devices for signs and the like and more particularly to a flashing device for gaseous conduction tubes such as the common neon tube now used in advertising displays.

It is the principal purpose of my invention to provide a device of this character wherein two sets of tubing may be operated from a single transformer so as to flash both sets without any danger of accidentally opening the secondary circuit of the transformer if one of the tubes of either set should fail.

It is also an important purpose of this invention to provide a device of this character which in opening the circuit through either set of tubing completely disconnects the tubing from the secondary of the transformer at both ends thereby avoiding any danger of corona discharge or other stray electrical disturbance. The circuits through the tubes is closed in exactly the same fashion, that is, both terminals are connected to the source at once.

It is also a purpose of my invention to provide a flashing device capable of connecting first one set of tubes and then another set across a source of current where two sets of tubes are being lighted from the same source in such fashion that the change-over is made quickly within a short period in which both sets of tubes are connected across the source of current.

My invention further contemplates the provision of a device of this character wherein a single driving device may be utilized to operate any number of flashing groups arranged in pairs up to the capacity of the operating unit.

It is a further purpose of my invention to provide in a flashing device of this character a novel actuating mechanism for shifting the contacts so as to connect the different sets of tubes alternately to the source of current supply. To this end my invention contemplates the provision of stationary contact pairs together with movable contact pairs carried by a rocking element and a novel mechanism for rocking said element so as to cause the contacts to separate with a snap action and to close both pairs of contacts before opening the previous closed one and closing the previous opened one.

I will describe the preferred form of my invention by reference to the accompanying drawings wherein—

Fig. 1 is a vertical section through the device; Fig. 2 is a plan section on line 2—2 of Fig. 3; Fig. 3 is a vertical section of a portion of the

device showing a different position than that shown in Fig. 1; and

Fig. 4 is a detailed section on line 4—4 of Fig. 3 showing the movable contact mechanism.

Referring now in detail to the drawings, the numeral 5 will be used to refer to one set of tubing and the numeral 6 refers to another set of tubing of the gaseous conduction type. I have shown the wiring for connecting the sets of tubes to the flashing device in connection with Fig. 2 where the set 5 is connected by wires 7 and 8 to terminals 9 and 10 respectively these terminals being mounted in the top of the porcelain housing 11.

The set of tubes numbered 6 is connected by 15 the wires 12 and 13 to the terminals 14 and 15 respectively and the source of current supply is connected by means of the wires 16 and 17 to the terminals 18 and 19 respectively.

Terminals 9, 10, 14 and 15 have stationary contact heads such as 20 and 21 (see Fig. 3) which are adapted to be engaged by the movable contact elements such as 22, 23, 24 and 25. Contacts 22 and 23 are supported by the movable contact member referred to generally by the numeral 26 and contacts 24 and 25 are supported by a similar member 27 and these two members are connected by means of an insulating member 28 which is supported at its opposite ends in suitable bearing blocks such as indicated at 29 in Fig. 3 as forming an extension downward of the terminal member 18.

A suitable arm 30 is secured substantially at the center of the member 28 and depends therefrom through a slot 31 in the insulating member 32 which forms a barrier separating the interior of the porcelain casing 11 from the operating mechanism for rocking the member 28. The arm 30 is also of insulating material preferably bakelite and the barrier 32 is preferably constructed of porcelain.

The lower end of the arm 30 is connected by means of a pin 33 to a yoke 34 which is actuated by pin 35 on wheel 36 to rock the arm 30 to and fro in a manner which will be more thoroughly described hereinafter. The yoke member 34 it will be noted has its lower end provided with a pin 37 which passes through an opening in the supporting member 38 and a suitable spring 39 urges the yoke member upward.

The gear wheel 36 is driven from a suitable pinion 40 (see Fig. 1) which pinion is driven by means of the induction disk 41 of the induction disk motor housed in the lower portion 42 of the casing.

It is obvious of course that the shaft 43 upon which the pinion 49 is mounted may be extended to provide driving mechanism for several more wheels such as wheel 36 when it is desired to 5 operate several of the flashing units from the single motive power source. The general structure of the device having been described, I will now describe in detail the several features which are important in the functioning of this mechanism.

First, I will refer to Fig. 2 where I show the conductors such as 44 and 45 mounted on the terminals 9 and 10 and a similar pair of conductors 46 and 47 mounted on terminals 14 and 15. The adjacent ends of these conductors are turned down (see Fig. 4) and they form an air path in parallel with the gaseous conduction path such as 5 or 6 so that in the event of failure of one of the tubes in a set such as 5 or 6, the high 20 voltage necessary to operate the tubes will, as it rises due to open circuiting of the secondary of the transformer, break down the air between the adjacent ends of the conductors. The spacing of conductors 44 and 45 is made such that only a 25 slight rise in voltage is necessary to establish the current flow across them thus protecting the transformer in the event of the breaking of the tubes and enabling me to provide continuous operation.

30 The contacts 22 and 23 mounted on the member 26 have the spring arms such as 48 and 49 and a bowed spring 50 has its opposite ends pressing the arms 48 and 49 upwardly. The intermediate portion of the spring 50 is bent over the pin 51 (see Fig. 1). Stops 52 and 53 limit the upward movements of the arms 48 and 49.

In order to insure good contact between the terminals such as 18 and 19 and the movable contact members such as 22 and 23, I preferably 40 provide the construction such as shown most clearly by Figs. 1 and 4. The terminal 18 has the bearing block 28 rigidly connected therewith so that it forms a good conducting path down to the shaft 54 which is mounted on the end of the 45 insulating rod 28 but this shaft must necessarily turn in its bearing and therefore may become loose which would adversely affect the conduction of current to the member 26 which is the contact carrying member and which of course is directly 50 connected to the spring arms 48 and 49. In order to further insure good conduction from the member 18 to the member 26, I provide a spring member 55 which is fixed at its upper end to the terminal 18 and which bears against the stub 55 shaft 54 at its lower end as indicated at 56. In this fashion I obtain assurance of good contact.

Referring now to the yoke 34 and its operation, this yoke, it will be noted, has a straight depending arm portion 57 (see Figs. 1 and 3) and then 60 has the body portion such as 58 opposite the straight portion 57 and has a lower portion 59 opposite which there is an opening to provide clearance as will now be explained.

Assuming that the pin 35 is being carried by 65 disk 36 in the direction of the arrow at the instant shown in Fig. 3, this pin is forcing the yoke to the right and thus moving member 30 to the right also. As the center line is passed, spring 39 snaps the yoke over to the right to the full limit permitted by the spring arm 49. This, of course, causes the yoke to move ahead of the pin 35 and the bow at 58 is provided to take care of this 70 action and avoid having pin 35 strike the yoke.

On the reverse action, the pin 35 will move 75 down into the dotted position shown in Fig. 1

to engage the portion 59 of the yoke and as it moves this portion 59 to the left, it will eventually cause the yoke to snap into left hand position thus moving contact 48 up against its stationary contact and the opening below the end 5 of the straight portion 57 provides clearance for the pin during this action.

The flashing device of itself essentially is made up of two consumption circuits each one of which comprises a set of gaseous conduction tubes and 10 a supply circuit consisting of a transformer and a suitable source of current. The present device provides a switching means adapted to continuously switch the current supply from one to the other of the consumption circuits 5 and 6 so as to 15 flash them on and off without breaking the supply circuit. This is an important feature in the present device because of the high open circuit voltage characteristics of transformers used for supplying current to gaseous conduction devices. 20

The operation of this device to flash two sets of tubing then is as follows. Assuming that the mechanism is in the position shown in Fig. 1, that is, with the current connected to terminals 14 and 15 through terminals 18 and 19 and contacts 23 and 25. Then pin 35 is moved clockwise to move the yoke 34 to the left thus bringing contacts 22 and 24 up into engagement with the contacts on the ends of terminals 9 and 10 respectively. This momentarily connects both sets of tubing to the 25 current supply. As pin 35 continues however, the yoke is snapped over by spring 39 to break the circuit to set 6 at both ends at once. Thus there is no opportunity for stray discharges of current. 30

From the above description it is believed that 35 the construction and operation of this device will be clear to those skilled in this art and the advantages readily apparent.

Having thus described my invention what I 40 claim as new and desire to secure by Letters Patent is:

In a flashing system having a pair of consumption circuits adapted to be alternately supplied with current and a supply circuit adapted to supply current to said consumption circuits, switching means for continuously shifting the current supply from one to the other of said consumption circuits without breaking the supply circuit, said means comprising a pair of spaced contacts adapted for connection to the terminals of one 45 consumption circuit, a second pair of spaced contacts adapted for connection to the terminals of the other consumption circuit, and a pair of spaced bridging contact members adapted for connection to the terminals of said supply circuit, 50 each bridging contact member having two contacts electrically connected together, means for moving said bridging members in unison between a position where one contact of each bridging member engages one of the first named pair of 55 stationary contacts and the opposite contact of each bridging member is spaced from the second named pair of stationary contacts and a position where said opposite contacts of the bridging members engage the second named pair of stationary contacts and the first named pair of stationary contacts are separated from the bridging members, said switching means including mechanism maintaining one contact of each bridging member in engagement with its respective stationary contact until the opposite contact thereof 60 makes contact with its respective stationary contact. 65

THOMAS J. MUDON.
